UNITED STATES PATENT OFFICE.

FRANK B. WERSEL, JR., OF CINCINNATI, OHIO.

HAMMOCK-COT.

1,138,820.

Specification of Letters Patent. Patented May 11, 1915.

Application filed May 1, 1914. Serial No. 835,581.

To all whom it may concern:

Be it known that I, FRANK B. WERSEL, Jr., a citizen of the United States of America, and resident of Cincinnati, county of Hamilton, State of Ohio, have invented certain new and useful Improvements in Hammock-Cots, of which the following is a specification.

This invention relates to improvements in hammock-cots and has for an object to produce a device which may be adapted for use as a hammock or as a cot.

A further object is to produce a device in which means are employed for adapting the device to be used as a crib or as a protected hammock or cot for out of door use.

A further object is to produce a hammock cot in which means are employed for giving the mattress of the device any desired degree of reclining inclination.

These and other objects are attained in the apparatus described in the following specification and illustrated in the accompanying drawings in which:

Figure 1 is a fragmental perspective view of my hammock-cot when it is adapted to be used as a hammock. Fig. 2 is a fragmental perspective view of one end of the device illustrated in Fig. 1. Fig. 3 is a fragmental perspective view illustrating wind shield and hanger securing details of my invention.

Fig. 4 is a fragmental sectional view intended to more clearly illustrate the curtain or wind shield securing means. Fig. 5 is a view showing the formation of one of the ends of the hangers. Figs. 6 and 7 are views showing the construction of the cot leg and its securing means. Fig. 8 is a perspective view illustrating my hammock cot adapted to use as a cot, with means mounted thereon adapted to afford protection against insects. Fig. 9 is an end view of the device as illustrated in Fig. 8. Fig. 10 is a detail of the means employed for removing and

40 storing the protective netting shown in Fig. 8. Fig. 11 is a perspective view showing my hammock cot adapted to be used as a crib. Fig. 12 is a perspective view showing the means for securing and elevating the

50 mattress to occupy different reclining positions. Fig. 13 is a fragmental sectional view of the mattress showing the means employed to aid in obtaining the various reclining positions of the mattress and Fig.

14 is a fragmental perspective view illustrating a portion of the wind shield and its securing means.

The hammock-cot illustrated as an embodiment of my invention comprises a frame 15, carrying the bed spring 16, hangers 17, 60 cot legs 18, wind shields 19, mattress 20, protecting netting and mounting frame 21, and mattress supporting means 22.

When the device is to be used as a hammock the combination of elements disclosed in Fig. 1, is used. This combination includes the frame 15, spring 16, hangers 17, mattress 20, mattress support members 22, and if desired, wind shields 19. The hangers are secured to the angle-iron frame 15 by having their off-set ends 17^a (see Fig. 5) passed through the diagonally extending slots 15^a formed in each end of each longitudinal angle-iron side member of the frame 15. In order to insert the off-set ends of the hangers in the diagonal slots, the hangers will have to be brought to an inclined position such that the off-set ends 17^a will be in alignment with the slots 15^a, in which position the ends will readily engage the slots, and the hangers may be brought to the vertical position illustrated, thereby locking the ends 17^a in the position shown. (See Fig. 3.) In this position it will be impossible for the ends of the hangers to become disengaged from the frame.

The hangers are provided at their upper ends with loops 17^b and their ends are adapted to be held apart by means of transverse braces 23. These braces or strips are provided at their ends with V shaped notches in which V shaped bends 17^c of the hangers, are located. These notches in braces 23 and co-operating bends 17^c prevent displacement of braces 23 longitudinally of the hangers 17. In order to prevent transverse displacement of the braces, plates 24 are provided in the split ends of each brace 23. These plates are provided with openings in which the bends 17^c are located and they are secured to the strips by means of nails or screws 25 driven through each brace 23 and through each plate 24, thereby securing the plate to the brace and preventing transverse displacement of the strip relatively to the hanger. I preferably provide curtains or wind shields 26 which are secured to each brace 23 in some suitable manner and at

their lower ends are secured to the transverse angle-iron members of frame 15 in any suitable manner as shown in Figs. 3 and 4. The hammock as thus described may be suitably suspended by chains 27 from the porch ceiling or from a support stand provided for the purpose.

In order to render the hammock more comfortable, the mattress 20 may be provided. This mattress is provided at its ends with boards 28, 29 in which hooks 30-31 are secured. These hooks are adapted to engage the links of the mattress support chain 22 which may be raised or lowered by engaging 15 any one of its several links in the hook of hammock suspending chain 27. The hooks mounted on the board secured in the end of the mattress opposite to that of the supported end, are adapted to be brought into 20 engagement with any one of the transverse wires of the bed spring as shown in Fig. 1, or they may be caused to engage openings 15^b in the horizontal flange of the angle-iron end member of the frame as shown in Fig. 25 12. The purpose of this is to prevent the foot of the mattress from creeping toward the head or inclined end thereof when it is in use.

Side inclosing wind shields 19 are adapted 30 to be removably secured to the plates 24 and the angle-iron side members of frame 15, in order to protect the occupant of the hammock. These wind shields are provided at their lower edges with longitudinal strips 35 19^a and at their upper edges with longitudinal strips 19^b. The strips 19^a are provided with screw eyes 19^c which are adapted to engage slots 15^c formed in the horizontal flanges of the side members of the frame. In order to secure these strips 19^a to the side frame-members, the screw eyes are turned into alinement with the slots 15^c and the strips 19^a are brought to engage the 40 under face of the horizontal flange of the longitudinal side members and the screw eyes are passed upwardly through slots 15^c. With the strips in this position the screw eyes are turned at right angles to the slots thereby securing the strips in position. The 45 upper strips 19^b of the wind shields are provided with slots at each of their ends adapted to engage the plates 24 and hooks 19^a, secured to the ends of strips 19^b, are caused to engage the openings 24^a in plates 50 24, thereby locking the strips 19^b in position.

With wind shields secured to both sides of the hammock, it is readily adapted to be used as a crib since protective siding is provided to entirely surround the frame and 60 mattress.

Should it be desired to use the device as a cot instead of a hammock, removable legs 18 may be readily secured to the frame 15.

With the legs secured in position, the

hangars 17 may be allowed to remain in place to provide support members for a roller 32 adapted to carry a mosquito bar netting 33 for the purpose of protecting the occupant of the cot against insects. It will thus be seen that the cot may be readily adapted to use out of doors.

Inclination of the head end of the mattress is obtained when the device is being used as a cot, by inserting the hooks at one end of the mattress in apertures 18^a formed 75 on the upper cross bars of the leg. (See Fig. 8.) In order to prevent the foot of the mattress from creeping toward the head portion thereof, when the head portion is elevated as shown in Fig. 8, the hooks 80 located in the foot of the mattress are inserted in apertures 15^b formed in the end bars of the frame 15, or they may be brought to engage the transverse wires of the bed spring as previously described.

In order to removably mount the legs of the cot, the means illustrated in Figs. 6 and 7 are provided. This means consists of plates 34 secured to the legs in the manner shown and having inwardly extending 90 hooked portions 34^a which are adapted to take over shoulder rivets 35 extending inwardly from the vertical flanges of the angle-iron side members of the frame 15. Removable pins 36 are adapted to pass through 95 the legs above the plates 34 and through apertures 15^d formed at the ends of the end angle-irons of the frame 15. It will thus be seen that the legs will be rigidly locked in position when the several parts occupy 100 the positions shown in Fig. 6. In securing the legs to the frame, each leg is brought into alinement with the longitudinal members of the frame and the hooked ends of the plates 34 are caused to pass over the 105 rivets 35. The legs and plates are now rotated about the rivets until they occupy a position at right angles to the frame. This brings the pin apertures in the leg into alinement with the apertures 15^d in the end 110 members of the frame. The pins 36 may now be easily placed in position thus locking the legs and frame securely together.

Having thus described my invention what I claim is:

1. In a hammock cot, the combination of a frame, legs removably secured to the frame, hangers removably secured to the frame adjacent to the legs, a roller removably mounted on said hangers, and fabric secured to 120 said roller, adapted to cover the hangers, legs and frame and to be rolled upon said roller when not in use.

2. In combination in a hammock cot, a frame, legs removably mounted on the 125 frame, hangers removably mounted on the frame adjacent to the legs, windshields removably secured to the hangers and the

frame, a mattress located on the frame and means adapted to support one end of the mattress in an inclined position relatively to the frame.

5. 3. A hammock cot comprising a frame having inclined slots located at the ends of said frame, shouldered rivets located at the ends of said frame adjacent to the slots, legs adapted to support said frame, hooked plates secured to the legs and adapted to engage the rivets to secure the legs to the frame, and hangers having offset ends adapted to engage the slots.

4. In a hammock cot the combination of a frame, hangers removably mounted on the frame, a mattress, and support members adapted to engage the hangers and the mattress to support the mattress in an inclined position relatively to the frame.

20. 5. In combination in a hammock cot, a frame, hangers secured to the frame and having bends formed therein, transverse braces having ends fitting the bends, plates having perforations engaging the bends and extending beyond the ends of the braces, longitudinal strips between the braces, means mounted on the strips adapted to removably engage the plates, and wind shields

secured to the longitudinal strips and the braces.

6. In combination in a hammock cot, a frame, hangers secured to the frame and having bends formed therein, transverse braces having ends fitting the bends, plates secured to the braces and having perforations engaging the bends and extending beyond the ends of the braces, longitudinal strips between the braces, hooks mounted upon the strips adapted to removably engage the plates and wind shields secured to the longitudinal strips and the braces.

7. In a hammock cot the combination of a frame, legs removably mounted on the frame, a mattress, and hooks located in the ends of the mattress adapted to engage the legs and the frame and to support the mattress in an inclined position relatively to the frame.

In testimony whereof, I have hereunto subscribed my name this 29th day of April, 1914.

FRANK B. WERSEL, JR.
